UNITED STATES PATENT OFFICE.

ELLISON SAUNDERS, OF AUSTIN, TEXAS.

SAFETY-STOP FOR ELEVATORS.

SPECIFICATION forming part of Letters Patent No. 295,678, dated March 25, 1884.

Application filed September 10, 1883. (No model.)

To all whom it may concern:

Be it known that I, ELLISON SAUNDERS, of Austin, in the county of Travis and State of Texas, have invented a new and Improved 5 Safety-Stop for Elevators, of which the following is a full, clear, and exact description.

The object of my invention is to provide a new and improved attachment for elevator-cars to stop the descending car immediately in case 10 the elevating-cable breaks.

The invention consists in a lever pivoted to the bottom of the car, and provided with a spring for throwing it into position transversely to the car-bottom, so that the ends of 15 the lever can catch on horizontal bars secured to the sides of the elevator-shaft. A rope or cable is secured to one end of the lever and to the car-elevating cable, and keeps the spring taut, and prevents it from throwing the 20 lever unless the elevating-cable breaks.

Reference is to be had to the accompanying drawings, forming part of this specification, in which similar letters of reference indicate corresponding parts in all the figures.

Figure 1 is a longitudinal outside elevation of an elevator-shaft containing an elevator-car provided with my improved attachment. Fig. 2 is a side view of the car. Fig. 3 is a sectional plan view of the shaft and a plan view of the 30 bottom of the car. Fig. 4 is a horizontal sectional view of the elevating-cable, with a part of the safety rope or chain attached.

On two opposite sides of the elevator-shaft a series of horizontal bars, B, are securely fastened to the corner-posts C of the shaft, which bars may be made of wood or metal, and can be spaced from about six inches to several feet. The bars B can extend entirely across the sides of the shaft, or can extend to a point slightly 40 beyond the middle of the sides of the shaft, at which point a standard must be erected. If the bars B extend entirely across the sides of the shaft, vertical struts D are placed between the bars at a point a short distance beyond the middle of the shaft. A lever, E, is pivoted to the bottom of the elevator-car A, at or near the middle of the same, which lever is of such length that it can extend from the outer sides of the bars B on one side of the shaft to the 45 outer sides of the bars B on the opposite side of the shaft, as shown. To one end of the le-

ver E a spring, F, is fastened, which has its opposite end secured to the bottom of the car, which spring can draw the lever E in such a manner that it extends transversely across the 55 bottom of the car, and so that the ends of the said lever project between the bars B. To that end of the lever E opposite the one to which the spring F is fastened a cable, rope, or chain, G, is fastened, which runs over pulleys H and H' at the bottom and top edges of the car, which cable G is provided at its upper end with a ring, K, or an eye or pulley-block, through which the elevator-cable J passes. As long as the cable J is taut, the 60 cable G is taut and draws the lever E in the inverse direction of that in which it is drawn by the spring F, thus keeping the entire lever E within the limits of the bottom of the car. If the elevating-cable J breaks, the cable G 65 will be slackened, and the spring F can draw the lever E to extend transversely across the bottom of the car, thus throwing both ends of the lever E between the bars B on the opposite sides of the shaft. The ends of the lever 70 E catch on the bars and prevent the car from descending. The car is thus prevented from dropping, and serious accidents can thus be prevented. As the ends of the lever E act 75 downward with great force on the bars B at 80 or near the middle, I have provided the struts D to counteract this pressure and prevent the pressure from breaking the bars B. The bottom of the car is provided with studs 85 M, to prevent the lever E from swinging too far in one direction or the other. The above-described device operates instantaneously, and will never fail to check the car in case the elevating-cable or the machinery for raising the car breaks.

A cord and weight can be used in place of the spring F.

Other suitable equivalent devices can be used in place of the bars B. For instance, grooves can be cut in the walls of the elevator-shaft, or brackets can be provided in place of the bars B.

Having thus described my invention, what I claim as new, and desire to secure by Letters Patent, is—

1. The combination, with an elevator-car, of a pivoted locking-lever on its bottom, and of

bars or analogous devices on the sides of the elevator-shaft, substantially as herein shown and described.

2. The combination, with an elevator-car, of 5 a lever pivoted to its bottom, a spring acting on the lever and tending to throw it in a transverse position, and a rope or cable secured to the opposite end of the lever, and provided at its upper end with an eye or ring, through to which the elevating-cable passes, substantially as herein shown and described.

3. The combination, with an elevator-car, of 15 a lever pivoted to the bottom of the same, a spring secured to one end of the lever and to the car, a rope secured to the opposite end of

the lever, and provided at its upper end with a ring through which the elevating-cable passes, and of horizontal bars or analogous devices secured to the sides of the shaft, substantially as herein shown and described. 20

4. The combination, with an elevator-car and a lever pivoted to the bottom of the same and acted on by a spring, of bars B B, secured to the posts C, and of the struts D, substantially as herein shown and described.

ELLISON SAUNDERS.
